UNITED STATES PATENT OFFICE.

JOHN JUHASZ, OF NEW YORK, N. Y.

CARBURETOR.

Application filed January 7, 1924. Serial No. 684,765.

The present invention relates to improvements in carburetors, more particularly to multinozzle carburetors of the type wherein each nozzle is disposed within an individual carbureting chamber, all chambers communicating with a single carburetor outlet, the communication being controlled by a throttle, common to all of said chambers. In carburetors of the general type specified the communications between the several carbureting chambers and the carburetor outlet are usually opened progressively, that is to say the carburetor nozzles are brought into service one after the other or at least one group is brought into service after another. In practice serious troubles have been experienced with carburetors of this type for the reason that the throttle does not fit airtight into the carburetor casing, so that at low engine speeds when only one of the carburetor nozzles is in service, fuel is drawn from the remaining nozzles and this fuel, not being able to pass to the carburetor outlet, drops to the bottom of the respective carbureting chamber, to be taken up by the air streams as these chambers are progressively opened. A too rich mixture is thus temporarily obtained when the remaining carburetor nozzles are brought into service, not speaking of the waste of fuel.

The main object of the present invention is to eliminate this trouble, that is to say to provide a carburetor which furnishes a proper fuel mixture at all times during the operation of the engine.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claim, without departing from the spirit or sacrificing any of the advantages of the invention.

One of the many possible embodiments of the invention is illustrated in the accompanying drawings, in which:—

Figure 1 is a top plan view of a carburetor constructed in accordance with the present invention; Fig. 2 is a sectional elevation of a portion of the carburetor; Fig. 3 is a central vertical section taken through one of the noz-

zles, on a larger scale; and Fig. 4 is a central vertical section taken through the several tubes of the nozzles.

In the drawings, the numeral 10 indicates a carburetor casing, in the side of which is formed an opening 11, forming the air inlet to the carbureting chambers 12, of which four are shown in the drawings (Fig. 1), although any other suitable number may be employed according to the requirements. These chambers are in the present case in the form of Venturi passages. Into each of these passages projects a fuel nozzle 13, which communicates with a float chamber 14 of any suitable construction, the inlet openings to the nozzles being controlled, for instance, by needle valves 15, although this is not essential. Above the carbureting chambers is disposed a throttle 16, in the present case a cylindrical throttle, for the well known purpose.

Each of the carburetor nozzles comprises a central tube 17, the bore 18 of which is provided with a plurality of sections of varying transverse cross section. The transverse cross sections of these bore sections gradually decrease from the uppermost section to the lowermost, as clearly shown in Fig. 3 of the drawings. The lower end of the tube is provided with a flange 19, on which rests the flange 20 of a tube 21, which encloses the said central tube and is spaced therefrom. The upper open end of the tube 21 is disposed a slight distance below the upper end of the central tube 17, onto the latter being fitted a cap 22, which extends a substantial distance downwards over the tube 21 and is spaced from the latter. The lower open end of the cap is outside the suction area of the tube 17, air flowing into the space between the tube 21 and the said cap at substantially atmospheric pressure. This air flows into the space between the tubes 17 and 21, and from the latter space into the tube 17, as will be presently described. The flanges 20 and 19 above referred to are disposed in a bore 23 in the carburetor casing, a gasket 24 being interposed between the flange 20 and a shoulder 25 in the said bore, the elements being held in proper position by a screw plug 26, having an aperture 27 in constant communication with the float chamber 14. The size of the aperture 27 corresponds, preferably, to that of the lowermost bore section of the jet, with which it communicates.

Each central tube 17 is provided with a plurality of holes 28, one associated with each

bore section. Through these holes the tube 17 is adapted to communicate with the space between the latter and the tube 21, as will be hereinafter further described. Each of 5 the bores 23 is closed by a screw plug 29, through which the screw-threaded stem of a needle valve 15 extends. When the plugs 26 and 29 are removed, each of the nozzles may be removed, as a unit, from the carburetor casing.

As above mentioned, the carburetor herein described includes four carbureting chambers, in each of which is disposed a fuel nozzle. Denoting these nozzles by the numerals I, II, III and IV, it will be observed 15 from Fig. 4 of the drawings, in which the central tubes 17 are illustrated diagrammatically, that they are of progressively increasing lengths, the shortest tube 17, indicated 20 at I, being disposed in the carbureting chamber denoted by the numeral I', that denoted by the numeral II being disposed in the carbureting chamber II', and so on. The throttle of the carburetor is so constructed that 25 the carbureting chamber I' communicates with the carburetor outlet, when the throttle is in its closed position, through a minimum opening which is sufficient to permit of a flow of air past the fuel nozzle I into a carbureting chamber so as to furnish combustible 30 mixture for the motor for idling. As the throttle is shifted toward opening position, the carbureting chambers II', III' and IV' are brought into action one after the other, 35 so that, when the throttle is in its fully open position, the four carbureting chambers are in action. In other words, during the opening movement of the throttle the nozzles are brought into service one after another, first 40 the shortest one of the nozzles being brought into service, then the next longer in the series, and so on. The flanges 19 of the several central tubes of the nozzles are disposed in the same horizontal plane. When, therefore, the 45 motor is at standstill the fuel level in the several central tubes, controlled by the float in the chamber 14, is at different distances measured from the tops of the said central tubes (see Fig. 4), it being nearest to the top of 50 the central tube of the nozzle I, the distance increasing obviously as the lengths of the nozzles increase. From this it appears that, when the engine is started and the carbureting chamber I' is in action, a combustible 55 mixture is formed in the said chamber, the suction of the engine transmitted to the chambers II', III' and IV' while the outlets of such chambers are closed being not sufficient to lift fuel from the nozzles II, III and IV,

as the fuel level in the tubes 17 of these nozzles, measured from the top of the latter, is 60 too low to permit fuel to be lifted therefrom. When the carbureting chamber II' is brought into action, and the suction, due to the increased engine speed, increased, fuel is furnished by the chambers I' and II', the suction being not sufficient to lift fuel from the nozzles III and IV, and so on. A proper mixture is thus obtained at all times during 65 the operation of the engine.

The holes 28 are provided in the central tubes 17 to permit air to be led into the same, the said holes being uncovered progressively as the level of fuel within the said tubes is lowered as the suction acting upon 70 the tubes 17 is increased.

Tests, which have been made with the carburetor herein described, show that the stepped cross-section of the bores of the nozzles give a material reduction in fuel consumption, and that this reduction in fuel consumption may result from improved atomization of the fuel. It appears that the stepped cross-section gives space for the increased volume due to the mixture of fuel 85 with the air which is vented through the holes 28.

It is obvious that, while herein specific nozzles have been described, any others may be used in connection with this invention, which 90 lies mainly in the provision of a carburetor having a plurality of independent carbureting chambers, each provided with a fuel nozzle, said nozzles being of different lengths and being brought into action progressively 95 from the shortest to the longest, as the engine speed increases.

What I claim is:—

A carburetor including a plurality of independent carbureting chambers, a throttle 100 for progressively bringing said carbureting chambers into service, and a suction controlled nozzle in each carbureting chamber, the lower ends of the bores of said nozzles being arranged at the same level and the 105 said bores being of different lengths so as to discharge at different levels, the lengths of the bores increasing in the order in which said carbureting chambers are brought into and maintained in service during the opening movement of said throttle, said bores being unobstructed and each bore gradually decreasing in transverse cross-section from its 110 upper end to its lower end.

Signed at New York, in the county of New 115 York, and State of New York, this 19th day of October, A. D. 1923.

JOHN JUHASZ.
